Patented Nov. 27, 1973

229,450

FLUID DISPENSING APPARATUS

Michael E. Croslin, Forest Hills, N.Y., assignor to
Grumman Data Systems Corporation, Bethpage, N.Y.

Original design application Sept. 17, 1969, Ser. No. 19,187,
now Patent No. 219,418. Divided and this application
Feb. 18, 1970, Ser. No. 21,499

Term of patent 14 years

Int. Cl. D15—08

U.S. Cl. D94—3

FIG. 2

FIG. 1

FIG. 4

FIG. 3

FIG. 1 is a side elevational view of a fluid dispensing apparatus showing my new design;

FIG. 2 is a rear elevational view thereof;

FIG. 3 is a top plan view thereof; and

FIG. 4 is a front elevational view thereof.

This is a division of design application Ser. No. D. 19,187, filed Sept. 17, 1969, now Design Patent No. D. 219,418.

I claim:

The ornamental design for a fluid dispensing apparatus, substantially as shown.
